UNITED STATES PATENT OFFICE.

JOSIAH V. WALDRON, OF NEW YORK, N. Y.

DESIGN FOR HARNESS-ROSETTE.

Specification forming part of Design No. **7,709**, dated August 25, 1874; application filed April 20, 1874.
[Term of Patent 7 years.]

To all whom it may concern:

Be it known that I, JOSIAH V. WALDRON, of the city, county, and State of New York, have invented a new and original Design for Harness-Rosette; and I do hereby declare the following to be a full, clear, and exact description thereof, which will enable those skilled in the art to make the same, reference being had to the accompanying drawing forming part of this specification, in which drawing—

Figure 1 represents a face view of my design. Fig. 2 is a side view of the same.

Similar letters indicate corresponding parts.

This design has for its object to impart an attractive and ornamental appearance to a rosette; and to such end it consists in forming the face-plate with an ornamental border, known as a Greek border or pattern, (illus-

trated by the raised lines *a*,) the sunken portions produced by such lines being delicately beaded or ornamented, as shown at *b*.

The border or pattern is inclosed by an ornamental border or beaded line, as at *C*; and said Greek border surrounds an annular raised center, *B d*, as shown, upon the center of which is secured or formed a conical-shaped protuberance or boss, *B*, in form closely resembling that of an acorn.

What I claim is—

The design for a rosette, the same being formed of the raised center *d*, acorn center, and surrounding Greek border or pattern, made up by the lines *a*, as herein shown and described.

J. V. WALDRON.
